TUBULAR HEAT EXCHANGE DEVICE

Harvey Feldmeier, Little Falls, N. Y., assignor to
 Cherry-Burrell Corporation, Wilmington, Del.,
 a corporation of Delaware

Application July 1, 1933, Serial No. 678,633

12 Claims. (Cl. 257—247)

This invention relates to improvements in tubular heat exchange devices for fluids, and more particularly to internal tube or double tube heat exchangers of that type used for heating or cooling liquids such, for example, as milk, in which the liquid or milk flows through inner tubes arranged within outer tubes through which flows the water or other medium for heating or cooling the milk or liquid. The tubes in devices of this type are commonly arranged in banks side by side or one above another, the internal tubes being connected at their ends by returns or headers to form a continuous zig-zag coil or conduit for one medium, and the outer tubes being likewise connected at their ends by returns or headers to form a continuous coil or conduit for the other medium. In order to insure complete draining of the fluids from the tubes of exchangers of this sort in which the connected tubes are disposed in different banks, it is usual to incline the tubes of adjacent banks in opposite directions, and also incline the connecting passages of the returns or headers so that the tubes and returns or headers will thus form a continuously inclined or descending conduit or passage for each fluid or medium.

Double tube heat exchangers of this character have been extensively used for many years, but long and varied experience has shown that such devices, as heretofore constructed, are open to various objections. This type of apparatus is subject to severe strains set up by unequal expansion and contraction in different parts thereof, due to temperature changes, and these strains cause leaks and bow or spring the tubes so as to interfere with their proper operation. For instance, in the use of such apparatus for treating the milk, they may be subjected at times to a cold milk temperature of say 50° F. and a sterilizing temperature of 200° F., or a temperature change of 150°. The expansion or contraction of the tubes in a twelve foot section under such a temperature change exceeds one-quarter of an inch and unless the apparatus is constructed so that the parts are free to take care of this movement in the tubes, which may be unequal in different parts of the coil or section, serious strains will be set up tending to bend or spring the tubes or loosen the joints.

One object of this invention is to produce a tubular heat exchanger of the sort mentioned of improved construction which will overcome objections to previous constructions.

Other objects of the invention are to produce a practical and efficient tubular heat exchanger

for fluids, of novel construction; also to provide such a device in which the section or coil is made up of tube units grouped together in a flexible way so that the whole coil or any part thereof is free to expand or contract without setting up undue strains in any part; also to join the tubes in an endless coil or conduit which is mounted on its supporting stand or structure so that the coil is free to expand or contract as if it were a long straight tube held at one end only; also to provide a support or stand of novel construction for heat exchange coils or sections which will adapt itself to unequal expansion and contraction or inequalities in the parts of the coil or section and will enable a more ready mounting of the coil or section on the stand or support; also to make a tubular heat exchanger of a construction which lends itself to economy in material, enabling a high grade apparatus to be produced at moderate cost; also to construct an apparatus, including the tubular coil or section and the support therefor which will be of neat, attractive appearance; also to provide a construction that allows any number of tubes, odd or even, in the coil or section, and makes it convenient to add or subtract tubes in installations in the field; also to provide individual returns for each pair of inner or outer tube ends, thus making it possible to have fluid connections for either the inner or outer tubes at any number of points in the coil or section necessary to give greatest efficiency; also to provide a construction by which the coil or section can be made with an even or odd number of tubes so that the inlets and outlets for the two fluids can be located at the same end of the coil or section or at opposite ends thereof; also to construct the coil or section with glanded connections between the tubes and returns so that the entire assembly is demountable and solder joints between the tubes and returns or headers are avoided. This is of particular advantage where chrome nickel steel tubes or other tubes that cannot be readily soldered are used. Also to provide a stand or support that holds the coil or section securely in place but is practically invisible; and also to produce a tubular heat exchanger which has the other features of improvement and advantage hereinafter described and set forth in the claims.

In the accompanying drawings:

Fig. 1 is a side elevation of a tubular heat exchanger embodying the invention.

Fig. 2 is an end elevation thereof, partly in section, on line 2—2, Fig. 1.

Fig. 3 is a transverse sectional elevation of one of the tube seats or saddles.

Fig. 4 is a side elevation thereof.

Fig. 5 is a broken longitudinal section through 5 one of the double tubes and outer tube returns.

The double tube heat exchanger illustrated in the drawings comprises outer tubes 10 arranged in two banks, one in front of the other, with the tubes of each bank arranged one above another, and the tubes in the different banks oppositely inclined, and a series of inner tubes 11, one extending concentrically through and spaced from each outer tube. The outer tubes are joined to form a continuous coil or conduit by returns 15 or headers 12 at the opposite ends of the tubes, each header 12 connecting one end of a tube in one bank with the corresponding end of an adjacent tube in the other bank. Preferably these returns or headers 12 at opposite ends of the 20 coil or section are oppositely inclined, as shown, so that the connected tubes 10 and headers 12 form a continuously inclined conduit or passage. The adjacent returns 12, or those at corresponding ends of the tubes, are separate from and 25 movable relatively to each other. The inner tubes 11 preferably are similarly connected to form a single continuous coil or conduit by returns or headers 13, each of which connects an inner tube in one bank with an adjacent inner tube in the other bank. These returns 13 also 30 are oppositely inclined at opposite ends of the tubes so that the inner coil or conduit inclines continuously in one direction.

The outer tubes 10 are removably secured to 35 the headers 12 preferably as shown in Fig. 5, the tube 10 being provided adjacent its ends with circumferential beads or projections 14 which are clamped between seats 15 in the headers and annular packings 16 adapted to be compressed 40 by adjustable glands 17 which, as shown, are screwed into the threaded openings in the headers which receive the ends of the tube 10. By screwing up the glands 17, the packings 16 are compressed and clamp the beads 14 against the 45 seats, thereby firmly securing the tube to the headers with liquid tight joints. While the headers are thus rigidly secured on the ends of the tubes and move therewith in the expansion 50 and contraction of the tubes, nevertheless the headers can be readily disconnected from the tubes by unscrewing the glands 17.

The inner tube 11 in each outer tube extends out through headers 12 at opposite ends of the outer tube and the joints between the inner tube 55 and the outer headers 12 are made liquid-tight by suitable packing means, such as packing rings 18 compressed between seats 19 in the headers 12 and glands 20 screwed into threaded holes in the headers 12, or otherwise adjustably connected to the headers, see Fig. 5. Preferably, 60 as shown in said figure, the inner tube is firmly but detachably secured in one return 12 by a circumferential collar or flange 21, fixed by sweating or otherwise, on the inner tube and clamped between the gland packing 18 and the 65 seat 19 in the return 12. By this construction the inner tube is rigidly secured near one end in one return 12 and the other end of the inner tube is adapted to move lengthwise in the packed 70 joint in the opposite return 12 to allow for any relative movement between these parts due to differential expansion and contraction in the inner and outer tubes.

Each return 12, as will be understood, is chambered to form a connecting passage 22 between

the corresponding ends of adjacent outer tubes in the two banks, and each return 13 for the inner tubes similarly is formed with a passage connecting corresponding ends of the adjacent inner tubes in the two banks. The returns 12 at each end of the coil are disconnected from each other and the returns 13 are also disconnected from each other. The several headers are therefore independently movable relatively to one another, so that no objectionable or injurious strain will be placed on the apparatus by reason of any differential expansion and contraction in different portions of the coil or section. Otherwise, the returns or headers may be of any suitable construction and preferably the returns 13 for the inner tubes are made with the usual hinged covers 23 which can be readily opened to afford access for cleaning the inner tubes. The returns 13 are also detachably secured to the tubes 11.

As usual, the internal coil is suitably equipped at its upper and lower ends for connection with supply or discharge pipes 25, 26 for milk or other liquid, and the outer coil is provided at its opposite ends with suitable fittings 27 and 28 for the admission or discharge of the water, brine or other medium which is circulated through the outer coil. In addition, any one or more of the intermediate returns 12 for the outer tubes can be replaced by a chambered header or fitting 30, 105 see Figs. 1 and 2, which is provided with a dividing wall or partition between the ends of the tubes connected by this header, which is suitably formed for the connection therewith of admission and discharge pipes 31, 32 so that one heating 110 or cooling medium, such as water, can be circulated through one portion of the section or coil, and a different medium, such as brine or water of a different temperature, circulated through another portion of the coil or section to make a 115 multiple stage heating or cooling coil.

The described construction, having the separate or independent headers 12, makes it possible to interpose one or more of the inlet and outlet headers 30 at any desired point or points in 120 the coil so as to divide the coil into two or more stages or portions of any desired number of tubes.

The coil or section, comprising tubes connected by separate, independently movable headers or 125 returns, as described, is mounted on a stand or support, preferably formed by connected uprights or posts 35, 36 arranged between the front and rear banks of tubes and provided with suitable feet or bases 27 and with forwardly and rearwardly projecting seats on which the tubes of the two banks rest and are supported. As shown, the posts 35 and 36 are rigidly connected by crossed diagonal brace rods 38 suitably fastened at their ends to the posts or uprights. Each tube seat is preferably formed by a saddle 39 having 130 a concaved segmental cylindrical top face 40 on which one outer tube 10 rests and which conforms substantially to the curvature of the tube and each saddle has a transversely grooved bottom lug or portion 41 which straddles and is adapted to rock on a stud 42 fixed to and projecting forwardly or rearwardly from the post or upright. The outer tube rests loosely in the concaved seat 440 and is adapted to slide lengthwise or turn 145 therein in any movement of the tube, due to expansion or contraction thereof, and the saddle is adapted to rock on the stud 42 in a vertical plane extending longitudinally of the tube and also to slide or shift on the stud, in a direction 150

- transverse to the tube. Each tube thus has a substantially universal rocking and sliding support on each upright. This manner of mounting the saddles or seats on the support or stand enables them to readily adapt themselves to the inclinations or positions of the tubes which they support and provide extended bearings for the tubes which, while they firmly support the coil or section, nevertheless permit relative movement between the section or parts thereof and the stand. The movable saddles thus insure amply large bearing surfaces for the several tubes notwithstanding possible irregularities or inaccuracies in the inclinations or positions of the tubes due to inaccuracy of manufacture or changes in position due to expansion and contraction of the tubes in operation. This result could not be secured by rigid or fixed seats for the tubes except by careful and much more expensive machine work, so that the stand with the movable saddles or bearings for the tubes can be produced at less expense and labor than a stand having rigid bearings or seats giving correspondingly extended bearings for the tubes.
- 25 The coil or section is secured at one point only in its length to the stand or support. For example, the free end of the uppermost tube of the coil is anchored, as by a rod 45, to the adjacent upright or post 35, but otherwise the section simply rests loosely on the tube saddles 39. Therefore, while the saddles retain the alinement of the tubes in the banks, the section is secured only at one point to the stand and the section as a whole or the various portions thereof are capable of movement relatively to the stand which prevents any binding or strain on the coil or stand or the parts thereof.
- I claim:
1. A tubular heat exchanger for fluids comprising a series of outer tubes, returns connecting said tubes to form a continuous outer conduit, inner tubes extending through said outer tubes and returns and joined to form a continuous inner conduit, said returns being separate and independently movable relatively to each other under expansion and contraction of the tubes, a support for said heat exchanger provided with seats having supporting surfaces of extended area on which said outer tubes rest movably, and means for retaining said heat exchanger in place on said support but leaving the heat exchanger free for movement relatively to said support under the expansion and contraction of said tubes, said seats being mounted to shift on said support in conformity with changes in positions of said tubes.
  2. A tubular heat exchanger for fluids comprising a series of outer tubes, returns connecting said tubes to form a continuous outer conduit, inner tubes extending through said outer tubes and returns and joined to form a continuous inner conduit, said returns being separate and independently movable relatively to each other under expansion and contraction of the tubes, a support for said heat exchanger having seats of extended area on which the several outer tubes rest movably and which have bearing contact with substantial surface areas of the tubes, and means connecting said heat exchanger at one point to said support and leaving said outer tubes free to move on said seats under expansion and contraction of the tubes, said seats being mounted on said support for movement relatively to each other.
  3. A tubular heat exchanger for fluids comprising a series of outer tubes, returns connecting said tubes to form a continuous outer conduit, inner tubes extending through said outer tubes and returns and joined to form a continuous inner conduit, said returns being separate and independently movable relatively to each other under expansion and contraction of the tubes, a support for said heat exchanger having seats of extended area on which the several outer tubes rest movably and which have bearing contact with substantial surface areas of the tubes, and means connecting said heat exchanger at one point to said support and leaving said outer tubes free to move on said seats under expansion and contraction of the tubes, said seats being mounted on said support for movement relatively to each other.
4. A tubular heat exchanger for fluids comprising a series of tubes, separate returns connecting said tubes to form a continuous zig-zag conduit, a support for said heat exchanger provided with seats which have bearing contact with relatively extensive areas of said outer tubes and on which the tubes rest movably, and means connecting said heat exchanger at one end only of said conduits to said support and leaving said outer tubes free to move on said seats under expansion and contraction of the tubes.
5. A tubular heat exchanger for fluids comprising a series of tubes, separate returns connecting said tubes to form a continuous zig-zag conduit, a support for said heat exchanger having seats on which the several tubes rest movably, said seats being capable of pivotal movement on said support in the planes of said tubes, and means for securing said heat exchanger at one point only thereof to said support and leaving said tubes free to move on said seats under expansion and contraction of said tubes.
6. A tubular heat exchanger for fluids comprising a series of tubes, separate returns connecting said tubes to form a continuous zig-zag conduit, and a support for said heat exchanger having seats on which the several tubes rest movably, said seats being movable on said support in the planes of said tubes and also in planes at right angles to said tubes, whereby said tubes are free to move relatively to each other under expansion and contraction of said tubes while remaining in place on said seats.
7. A tubular heat exchanger for fluids comprising a series of tubes, separate returns connecting said tubes to form a continuous zig-zag conduit, a support for said heat exchanger provided with pivoted seats on which each of said tubes rests movably to provide a substantially universally movable connection for each tube with the support, and means for securing said heat exchanger at one point only thereof to said support and leaving said tubes free to move on said seats under expansion and contraction of said tubes.
8. A tubular heat exchanger for fluids comprising a series of tubes, separate returns connecting said tubes to form a continuous zig-zag conduit, an upright support for said heat exchanger provided with laterally projecting studs, saddles pivotally movable on said studs and each movably supporting one of said tubes, and securing means which retain said tubes on said saddles.
9. A tubular heat exchanger for fluids comprising tubes arranged in spaced-apart banks, separate returns connecting the tubes to form a continuous conduit which is formed in part by the tubes in each bank, an upright support for said heat exchanger arranged between said banks of tubes and provided with laterally projecting seats on which the tubes of one bank rest movably and with oppositely projecting seats on which the tubes of the other bank rest movably, said

seats being relatively movable to accommodate their positions to different positions of the tubes.

10. A tubular heat exchanger for fluids comprising tubes arranged in parallel banks with the tubes in different banks oppositely inclined, separate returns connecting the tubes to form a single continuously inclined conduit, an upright support for said heat exchanger arranged between said banks of tubes and provided with laterally projecting seats on which the tubes of one bank rest movably and with oppositely projecting seats on which the tubes of the other bank rest movably, said several seats being relatively movable.

11. A tubular heat exchanger for fluids comprising tubes arranged in parallel banks with the tubes in different banks oppositely inclined, returns connecting the tubes to form a continuous conduit, a supporting stand for said heat exchanger comprising connected uprights arranged between the banks of tubes, seats projecting lat-

erally from said uprights for each tube in one bank, and seats projecting oppositely from said uprights for each tube in another bank, said tubes resting movably on said seats, said seats being mounted for movement relatively to each other and means movably retaining said tubes in place on said seats.

12. A tubular heat exchanger for fluids comprising a series of tubes, separate returns connecting said tubes to form a continuous zig-zag conduit, a support for said heat exchanger having seats on which the several tubes rest movably, said seats being mounted to shift on said support in conformity with changes in positions of said tubes, and said tubes being free to move on said seats and being movable relatively to each other under expansion and contraction of said tubes.
